BLOCK

Lyle E. Wright, Lanham, Md., assignor to Universal Building Products Corporation, Washington, D.C.

Filed Oct. 3, 1966, Ser. No. 4,121

Term of patent 14 years

(Cl. D18—2)

FIGURE 1 is a perspective view of block showing my new design;

FIGURE 2 is a top plan view thereof on reduced scale;
FIGURE 3 is a side elevational view;

FIGURE 4 is an end elevational view thereof;

FIGURE 5 is an end view showing a modification with two grooves in each section thereof; and

FIGURE 6 is an end elevational view showing a further modified form of the invention.

The characteristic features of my new design reside in the provision of a block of rectangular form having flat forward and rear faces and uninterrupted side and end edges with flat groove sections and sloping merger sections, with indented portions intermediate the groove sections and merger portions.

I claim:

The ornamental design for a block, as shown and described.
